CLAIM

I claim the ornamental design for a multifunction paper cutter, as shown and described.

DESCRIPTION

FIG. 1 is a first perspective view of a multifunction paper cutter showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a perspective view of FIG. 1 in a first use state; and, FIG. 10 is another perspective view in a second use state. The broken lines in the drawings depict portions of the multifunction paper cutter that form no part of the claimed design.

1 Claim, 10 Drawing Sheets
